UNITED STATES PATENT OFFICE

FRED STEBLER, OF RIVERSIDE, CALIFORNIA, ASSIGNOR TO STEBLER PARKER CO., OF RIVERSIDE, CALIFORNIA, A CORPORATION OF CALIFORNIA

INTERSECTION CONTROLLING APPARATUS FOR CONVEYERS

Application filed July 22, 1929. Serial No. 380,040.

This invention relates to conveyers and while the invention may be applied to conveyers used for various purposes, it is intended to be particularly useful when applied for conveying boxes or similar articles. In the operation of such conveyers it is common to provide lateral conveyers which deliver the articles such as boxes to the main conveyer. It is desirable to avoid collision between boxes at the intersections of the laterals with the main conveyer. In order to prevent such collisions means have been employed controlled by the presence of a box on the main conveyer and moving toward the intersection, for temporarily arresting the operation of the lateral.

This permits the box on the main conveyer to avoid collision with the boxes advancing from the lateral because the movement of the boxes on the lateral is delayed until the box on the main conveyer has passed the intersection. However, with the apparatus described above, it frequently happens that the arrest of the movement of the lateral conveyer will occur just at a time it is in the act of delivering a box to the main conveyer in such a way that a box will be left standing on the lateral conveyer projecting into the path of the box on the main conveyer.

The general object of this invention is to overcome this difficulty and to provide simple means for insuring that when the movement of the lateral conveyer is arrested, no boxes can be left projecting into the intersection so as to cause a collision with boxes moving forward on the main conveyer.

A further object of the invention is to improve the general construction of conveyers of this type in which laterals deliver into a main conveyer.

Further objects of the invention will appear hereinafter.

The invention consists in the novel parts and combination of parts to be described hereinafter, all of which contribute to produce an efficient intersection controlling apparatus for conveyers.

A preferred embodiment of the invention is described in the following specification,

while the broad scope of the invention is pointed out in the appended claims.

In the drawings:

Fig. 1 is a plan of a conveyer apparatus embodying my invention and showing a short section of a main conveyer together with the adjacent end of a lateral conveyer heading into it.

Fig. 2 is a side elevation of the apparatus shown in Fig. 1.

Fig. 3 is a view showing a portion of the lateral conveyer in side elevation and the main conveyer in cross-section as viewed from the plane of the line 3-3 of Fig. 1.

Before proceeding to a detailed description of the preferred embodiment of the invention, it should be stated that according to my invention I provide means between the delivery end of the lateral conveyer and the main conveyer which operates when the lateral conveyer is arrested to advance any article left standing at the end of the lateral conveyer and pass it on to the main conveyer.

In the preferred embodiment of the invention this conveyer means between the lateral and the main conveyer is positively driven but if desired it will be evident that gravity apparatus could be used at this point.

Referring more particularly to the drawings, 1 represents a main conveyer which is supposed to be fed by a plurality of laterals one of which is indicated by the numeral 2. Any suitable conveyer means may be used for the main conveyer and the lateral, that is to say, any means that operates to advance a load or boxes or other articles. In the present instance the main conveyer comprises a frame 3 supporting a continuously driven belt 4 which belt is driven in the direction of the arrow indicated in Fig. 1, that is to say, from right to left. The lateral conveyer 2 may also be in the form of a continuously driven belt which at its delivery end passes around a roller 5 supported in the frame 6 of the lateral.

In applying my invention, I leave a considerable space between the roller 5 and the side of the main conveyer 1 and in this space I provide feeding means 7 for advancing

an article left standing by the inhibition of the lateral conveyer. If this means is gravity controlled, then the level of the belt 2 would be slightly higher than the level of 5 the belt 4 so as to insure efficient movement by gravity of the box or other article onto the main conveyer.

As it is usual, however, for the laterals to be at the same level as the main conveyer, I 10 prefer to provide intermediate conveyer means 7 which is positively driven.

In order to effect the driving of the lateral from the main conveyer and at the same time to effect its automatic control, I provide the 15 main conveyer with a longitudinally extending shaft 8 which may run along below the level of the belt 4. This shaft affords means for driving the shaft 9 of the roller 5 to drive the lateral. Any suitable means may be employed for this purpose but in the present instance I have indicated an endless chain 10 for accomplishing this, said chain running over sprocket wheels 11 and 12 located respectively on the shaft 8 and the shaft 9. 20 In order to inhibit the action of the lateral 2 automatically by the presence of a box or other article passing along on the main conveyer and approaching the intersection indicated at 13, I prefer to mount the sprocket 25 wheel 12 loose on the shaft 9 and provide a clutch 14 on this shaft including movable cone collar 15 which is normally held inwardly so as to keep the clutch closed, by means of a coil spring 16. This cone is provided with an operating lever 17 of bell crank type having an arm 18 that extends across from the fulcrum pin 19 under the main conveyer 4 so as to bring its actuating end into position to be controlled automatically by a box passing along the conveyer 4. For this purpose I prefer to provide a rubbing bar 20 that is supported on the ends of two levers 21 and 22 that project into the space above the belt 4.

25 These levers preferably incline toward the direction the main belt 4 travels and are parallel with each other. These levers are pivotally mounted on suitable brackets 23 attached to the frame of the main conveyer. The lever 21 is attached to the upper end of a vertical shaft 24, the lower end of which carries rigidly a short arm 25 with a slot 27 carrying a pin or bolt 26 that is mounted in the operating end of the lever 18. With this construction and arrangement of parts, it will be evident that when a box coming along the conveyer 4 strikes the lever 22 and bar 20, it will swing the bar 20 in the direction of the arrow and this will 30 rock the lever 21 in an anti-clockwise direction. This will swing the arm 25 in the same anti-clockwise direction and will cause the lever 17 to swing in the direction indicated by the arrow on it thereby opening the clutch 14. This will arrest the driving of the lat-

eral conveyer 2. The intermediate conveyer means 7 for advancing any box or article left standing by reason of the stopping of the conveyer 2 preferably consists of a short 70 conveyer means composed of rollers and these rollers are preferably mounted so that they will support part of the weight of a box projecting beyond the end of the lateral conveyer deliver the box onto the main conveyer in the general direction in which that conveyer moves. In the present instance, I provide two radially disposed rollers 28 mounted on shafts 29, the axes of which, if extended, would intersect each other. These shafts are mounted in curved metal side bars 30 that may form part of the frame of the conveyer 2.

I provide for driving these rollers off of the shaft 8 for which purpose the shaft 8 is provided with a sprocket wheel 31 driving an endless chain 32 that is located to one side of the feeding means 7 and on the convex side of the adjacent curved bar 30, and passes over a sprocket wheel 33 on the shaft of the roller 28 that is farthest from the main conveyer 2 and whose shaft is substantially parallel with the shaft 8. The rotation of this roller 28 is communicated by a beveled gear 34 to an idle beveled gear 35 that in turn meshes with a beveled gear 36 on the shaft of the other roller 28. The idle bevel gear 35 may be carried on the end of a shaft or bar 37 the ends of which are supported in the side bars 30. These bevel gears are located on the concave side of the curved bar and on the side of the feeding means 7 toward which the main conveyer is moving.

It will be noted that the bars 30 are curved in a general direction around the point of intersection of the axes of the rollers 28, as 105 a center.

If desired, between the rollers 28 and the conveyer belt 4, a horizontal roller 38 may be mounted on suitable brackets on the side of the main conveyer frame.

In order to accommodate boxes coming in 110 from the lateral and prevent their being shoved off of the side of the conveyer belt 4 opposite to the lateral, I may provide a guard rail 39 of curved form and located as indicated in Fig. 1. Opposite this guard rail a 115 guide roller 40 mounted to rotate on a fixed vertical axis may be provided to facilitate the guiding of the boxes from the lateral properly onto the main conveyer, and this roller of course in doing this cooperates with 120 the guard rail 39.

In the operation of this apparatus when a box traveling along the main conveyer 1 strikes the bar 20, it deflects it and thereby rotates the shaft 24 which swings the lever 17 in a direction to open the clutch thereby stopping the movement of the belt 2 and any boxes located on the belt. If any of these boxes on the belt project over onto the conveyer means 7 they will be immediately ad- 130

vanced into the intersection 13 and onto the belt 4. This will occur before the box that has moved the bar 20 arrives at the intersection.

It is understood that the embodiment of the invention described herein is only one of the many embodiments this invention may take, and I do not wish to be limited in the practice of the invention, nor in the claims, to the particular embodiment set forth.

What I claim is:

1. In apparatus of the kind described, the combination of a continuously driven main conveyer, a lateral conveyer having its discharge end adjacent the main conveyer, automatic means controlled by an article advancing on the main conveyer for stopping the lateral conveyer to delay articles advancing on the same into the intersection with the main conveyer, roller means located in longitudinal alinement with the lateral conveyer and located between the discharge end of the lateral conveyer and the main conveyer so as to support part of the weight of an article on the end of the lateral conveyer and projecting beyond the end of the lateral conveyer, and means other than the article for positively driving the last-named roller means to effect the advance of any article projecting onto the same when the lateral conveyer stops.

2. In apparatus of the kind described, the combination of a continuously driven main conveyer, a lateral conveyer having its discharge end adjacent to the main conveyer, automatic means controlled by an article advancing on the main conveyer for stopping the lateral conveyer to delay articles advancing on the same into the intersection with the main conveyer, and feeding means located between the discharge end of the lateral conveyer and the main conveyer, said feeding means including a pair of driven rollers mounted with their axes converging toward each other and cooperating to deliver a box from the lateral conveyer on to the main conveyer in the general direction in which the main conveyer is moving, one of said rollers being located adjacent to the delivery end of the lateral conveyer so as to advance any article left standing on the lateral conveyer and projecting beyond its end, onto the main conveyer.

3. In apparatus of the kind described, the combination of a continuously driven main conveyer, a lateral conveyer having its discharge end adjacent to the main conveyer, automatic means controlled by an article advancing on the main conveyer for stopping the lateral conveyer to delay articles advancing on the same into the intersection with the main conveyer, a roller located adjacent the delivery end of the lateral conveyer, means for driving the same, a second roller located with its axis on a line intersecting the axis

of the last-named roller for cooperating with the last-named roller to deliver articles from the lateral conveyer onto the main conveyer, means for positively driving the first-named roller at one end, and means at the other end of the driven roller for driving the second-named roller.

Signed at Riverside, California, this 13 day of July, 1929.

FRED STEBLER.
